UNITED STATES PATENT OFFICE.

DAVID ROSS McGREGOR, OF SPRINGFIELD, OHIO, ASSIGNOR TO THE McSAVANEY COMPANY, OF SPRINGFIELD, OHIO, A CORPORATION OF OHIO.

MOUNTING FOR ELECTRIC-LIGHT BULBS.

Application filed September 8, 1924. Serial No. 736,429.

My invention relates to an improved mounting for electric light bulbs, it particularly relating to a mounting which is especially designed for installation in electric signs.

One of the objects of the invention is to provide a mounting so constructed as to permit the line wires to be readily connected thereto without the necessity of cutting or bending the wires; and, further, in this connection to provide an arrangement whereby the line wires may be extended over a series of the mountings so as to connect the lines in multiple and at the same time allow the line wires to be strung in straight parallel lines throughout the casing of the sign without bending or cutting.

A further object of the invention is to provide in a mounting of the twin type a simple and effective arrangement of terminals and electrical connections for conveying the current to the light bulbs.

A further object of the invention is to provide a mounting which will be simple in construction, economical in manufacture, easily installed and effective in use.

Referring to the drawings:

Fig. 1 is a side elevation of a mounting embodying the improvements.

Fig. 2 is an end view of the same.

Fig. 3 is a section on the line 3—3 of Fig. 2.

Fig. 4 is a top plan view of two of the mountings shown installed in the casing of the sign which is illustrated in transverse section.

Referring to the drawings, the mounting comprises a base 1, a pair of sockets 2 and 3, divided by a division wall 4, and a pair of oppositely-extending laterally-projecting line wire supports 5 and 6, all integrally formed from porcelain or other suitable insulating material. Each end of the base 1 is provided with an open ended slot 7 to receive suitable fastening devices by which the mounting may be secured in position on the bottom 8 of the casing of the sign, the sides of which are indicated at 9 and one end at 9' in Fig. 4. The walls of the socket 3 are provided with openings 11 for the purpose explained below.

Each socket has a metal bushing 12 and 13, the inner end of each bushing having an inturned flange 14 to receive a series of screws 15 which extend through the division

wall 14 to hold the sockets in position and to also act as conductors for the current. Secured on each side of the division wall 4 is a metal terminal piece 16 and 16' which terminals are secured in position by a screw 60 bolt 17 which passes through the division wall 4. This screw 17 also secures in position against the division wall a metallic conductor strip 18 which projects out through the opening 11 of the socket 3 and lies 65 against the face of the supporting member 6, being secured thereto by the screw 19. The outer end of this conductor strip 18 is provided with an upwardly projecting portion 20 which is bent laterally as indicated at 21 70 in Fig. 4 and is threaded to receive a binding screw 25 which serves to clamp one or the line wires 26 to an upturned lip 24 projecting from one of the sides of the portion 21. A similar metallic conductor strip 27 75 is secured by the screw 28 to the other supporting member 5 and projects through the opening 10 of the socket 3 and is secured by one of the screws 15. This strip 27 is likewise formed with an upwardly projecting 80 extension 29 bent laterally as indicated at 30 in Fig. 4 and threaded to receive a binding screw 31 which serves to clamp the other line wire 32 to an upturned lip 31. The light bulbs 33 are screwed in the bushings 85 in contact with the terminals 16 and 16'.

The circuit is as follows: from line wire 26 through strip 18 to terminal 16, bulb 33, bushing 13, terminal strip 27, to line wire 32; also from line wire 26, through strip 18, 90 screw 17, terminal 16', bulb 33', bushing 12, screws 15, conductor strip 27 to line wire 32.

By this construction, particularly the provision of the laterally-projecting supports 5 and 6, it will be seen that the line wires 26 and 32 may be strung along a series of mountings such as shown in Fig. 4 and may be secured to each mounting without the necessity of cutting or bending the wires; further, the arrangement of sockets, bushings, terminals and conductors is one which is simple, permitting the ready assembling of the parts as well as being economical in manufacture.

Having thus described my invention I 105 claim:

1. In a mounting of the character described, a supporting base member, a pair of aligned oppositely-projecting socket members, a division wall member between 110

said socket members, and laterally and oppositely-projecting conductor supporting members, said base member projecting in the direction of the longitudinal axes of said socket members and beyond the same, those portions which extend beyond the socket being apertured to receive fastening devices, all of said members being integrally formed of insulating material, conductor strips carried by the upper portions of said laterally projecting supporting members, and means for attaching line wires to said conductor strips so that the line wires will project in parallel relation with the axes of said socket members along the upper side of the mounting and above the supporting base.

2. In a mounting of the character described, a supporting base member, a pair of aligned socket members, a division wall member between said socket members, and oppositely-projecting laterally-extending conductor supporting members, all of said members being integrally formed of insulating material, said supporting base member being extended in the direction of the longitudinal axes of said socket members in a plane below said socket members, said conductor supporting members cooperating with said base member to support the mounting and being projected upwardly from said supporting base member to a point adjacent the upper portions of said socket members, conductor strips carried by the upper por-

tions of said supporting members, and means for attaching line wires to said conductor strips so that the line wires will project in parallel relation with the axes of said socket members and be supported above the supporting base member.

3. In a mounting of the character described, a base, oppositely extending aligned sockets, a division wall between the sockets, and oppositely extending lateral supports, all integrally formed of insulating material, a conductor strip on each support together with means for attaching line wires to said conductor strips, said conductor strips being extended through apertures in the wall of one of said sockets, a threaded metallic bushing in each socket, metallic fastening means common to both of said bushings and extending through said division wall for securing said bushings in position and also act as conductors, a pair of light bulb terminals, one in the rear end of each socket, a metallic fastening device extending through said division wall for securing said terminals in position and to act as a conductor, the terminal in the apertured socket being in electrical contact with one of said conductor strips and the bushing of that socket being in electrical contact with the other of said conductor strips.

In testimony whereof, I have hereunto set my hand this 25th day of August, 1924.

DAVID ROSS McGREGOR.
